UNITED STATES PATENT OFFICE.

ARTHUR B. CLUNIES, OF ROCHESTER, NEW YORK, ASSIGNOR TO THE SILL
STOVE WORKS, OF SAME PLACE.

DESIGN FOR A FIRE-POT FOR STOVES.

SPECIFICATION forming part of Design No. 32,709, dated May 22, 1900.

Application filed April 13, 1900. Serial No. 12,776. Term of patent 14 years.

To all whom it may concern:

Be it known that I, ARTHUR B. CLUNIES, a citizen of the United States, residing at Rochester, county of Monroe, and State of New York, have invented and produced a new and original Design for Fire-Pots for Stoves; and I do hereby declare the following to be a full, clear, and exact description of the same in connection with the accompanying drawings, forming a part thereof.

Figure 1 in the accompanying drawings shows a perspective view of a fire-pot embodying my design; Fig. 2, a bottom plan view, and Fig. 3 a side elevation.

The design, as shown in the drawings, embodies a fire-pot circular in form and somewhat tapering toward the bottom, having its

sides grooved or corrugated, as at 1. The upper edge is provided with a laterally-extending flange 2 and the lugs, or ears 3, and the lower end with a vertically-extending flange 4 and lugs 5 and 6, while above the lower edge of this latter is provided a vertically-corrugated or waved surface 7, this latter forming the characteristic or central feature of the design.

I claim as my invention—

The design for a fire-pot for stoves substantially as herein shown and described.

ARTHUR B. CLUNIES.
